FIG. 2

by

Baker, Wall & Cheek ATTORNEYS.

UNITED STATES PATENT OFFICE.

GEORGE W. WALLACE, OF EAST ST. LOUIS, ILLINOIS, ASSIGNOR, BY MESNE ASSIGNMENTS, TO ECONOMIC CARBONIZATION COMPANY, A CORPORATION OF DELAWARE.

VERTICAL RETORT.

Application filed January 3, 1921. Serial No. 434,525.

To all whom it may concern:

Be it known that I, GEORGE W. WALLACE, a citizen of the United States, residing at East St. Louis, Illinois, have invented a certain new and useful Improvement in Vertical Retorts, of which the following is a full, clear, and exact description, such as will enable others skilled in the art to which it appertains to make and use the same.

10 This invention relates to vertical retorts of the kind that are used for distilling oil shale, coal and other bituminous substances.

My present invention relates to a retort of the type described in my prior apparatus 15 Patent No. 1,283,001, dated October 29, 1918, that is equipped with a perforated take-off duct which constitutes the sole outlet for the gases, vapors and liquids evolved in the distilling operation and which is arranged in 20 the retort in such a manner that it can be lowered into a pit located beneath the retort so as to discharge the contents of the retort at the termination of the distilling operation.

25 In the retort described in my said prior patent the lower end of the take-off duct communicates with an off-take pipe or eduction pipe that has to be disconnected from the lower end of the retort and swung laterally out of alignment with the retort before

30 the take-off duct can be lowered into the pit to discharge the contents of the retort. There is a sealed joint between the removable bottom of the retort and the lower edge 35 of the side wall of the retort and the eduction pipe is also connected to the bottom portion of the retort by a sealed joint, thus requiring two sealed joints to be broken each time the retort is discharged. Furthermore, 40 it is necessary with such a retort to have a workman go into the pit and break the seal that connects the eduction pipe to the lower end portion of the retort and then swing said eduction pipe out of the way 45 before the bottom closure for the retort can be opened.

The main object of my present invention is to provide a retort of the general type above referred to which is so constructed 50 that it is not necessary to use a separate sealed joint between the lower end of the take-off duct and the eduction pipe or suction main through which the evolved gases, vapors and liquids escape from the take-off duct.

Another object is to provide a retort of the general type referred to which is so constructed that it is not necessary to have a workman go into the pit, disconnect the eduction pipe from the lower end of the retort and move said eduction pipe into an inoperative position prior to lowering the take-off duct into the pit to discharge the contents of the retort.

Another object is to provide a retort for 65 practicing the process described in my prior process Patent No. 1,283,001, dated October 29, 1918, which is of such design that it is practicable to arrange a number of relatively large retorts in a bench or single setting.

And still another object is to provide a vertical retort of the type that is equipped with a perforated take-off duct which is so constructed that the portion of said take-off 75 duct through which the gases, vapors and liquids escape to the suction main can be cleaned out when the take-off duct is arranged in operative position in the retort and without the necessity of first disconnecting the take-off duct from the suction main or eduction pipe. Other objects and desirable features of my invention will be hereinafter pointed out.

To this end I have devised a vertical retort that is of substantially oblong shape in horizontal cross section and which is equipped with a perforated take-off duct arranged inside of same and of corresponding shape in horizontal cross section. The retort is provided at its lower end with an extension equipped with a removable closure or cover, and the take-off duct is provided with a discharge portion that terminates inside of said extension and communicates with a lateral outlet on said extension which leads to a suction main or off-take pipe in which a suction or partial vacuum is created so as to cause the gases, vapors and liquids evolved in the distilling operation to pass inwardly through the coolest portion of the material in the distilling chamber, into the take-off duct and thence travel downwardly through said take-off duct to the suction main, according to the process disclosed in my prior process Patent No. 1,283,001, dated October 29, 1918. The take-off duct is adapted to be lowered into a pit by hoisting mechanism arranged above the retort, and the take-off duct 100 105 110

is preferably provided adjacent its lower end with a laterally projecting flange that serves to separate the distilling chamber of the retort from the extension at the 5 lower end of the retort in which the discharge portion of the take-off duct is located during the distilling operation. By constructing the apparatus in the manner above described I overcome the necessity of providing a separate sealed joint between the 10 take-off duct and the eduction pipe, due, of course, to the fact that the joint between the take-off duct and the eduction pipe is located within the extension at the lower 15 end of the retort, which extension is sealed or cut off from the atmosphere by the removable closure or cover arranged at the lower end of said extension.

Figure 1 of the drawings is a vertical longitudinal sectional view of a retort constructed in accordance with my invention.

Figure 2 is a vertical transverse sectional view of the retort shown in Figure 1; and

Figure 3 is a horizontal sectional view of 25 said retort.

Referring to the drawings which illustrate the preferred form of my invention, A designates a vertical retort which is of substantially oblong shape in horizontal 30 cross section, as shown in Figure 3, and B designates a perforated take-off duct inside of said retort which constitutes the sole outlet for the gases, vapors and liquids evolved in the distilling operation, the take-off duct 35 B extending vertically through the retort and being provided with orifices 1 through which the gases, vapors and liquids escape into the take-off duct from the distilling chamber. The upper end of the take-off duct 40 is closed and the lower end of said take-off duct communicates with a suction main or eduction pipe C in which a partial vacuum or suction is created so as to cause the gases, vapors and liquids evolved from 45 the material in the distilling chamber that surrounds the take-off duct to pass into the take-off duct through the orifices 1 in same and then flow downwardly through same to the eduction pipe C before said gases, vapors 50 and liquids can undergo secondary decomposition, the retort A being heated externally by any suitable means, such, for example, as gas flues D arranged at the sides of same, as shown in Figure 2.

55 The retort A can be constructed from any suitable material and it can be either a monolithic structure or a built up structure. In the form of my invention herein illustrated the retort is constructed of tile that 60 are formed of fire clay or silica and which are provided with co-operating tongues and grooves so as to prevent the escape of the gases and vapors from the distilling chamber. The retort is provided at its lower 65 end with an extension E, preferably made

of metal and formed either by a single hollow member or a plurality of superimposed sleeves that conform in general outline to the horizontal cross sectional shape of the retort, said extension being provided with 70 a removable cover E' that forms a closure for the bottom end of the retort. The upper end of the retort is closed by a removable cover F that is seated in a metal collar G arranged at the upper end of the retort. 75

The take-off duct B can be constructed from any suitable material, but said take-off duct preferably consists of a shell connected at its upper end to a head piece 2 that is adapted to co-operate with a hoisting mechanism 2^a and connected at its lower end to a discharge portion H equipped with an inclined discharge spout 3 whose lower end communicates with a lateral outlet 4 on the extension E of the retort which leads 85 to the suction main or eduction pipe C, as shown in Figure 1. When the take-off duct is arranged in operative position in the retort the discharge spout 3 of said take-off duct will be located within the extension E at the 90 lower end of the retort. Consequently, it is not necessary to use a gasket or other sealing device in the joint between the discharge spout 3 of the take-off duct and the lateral outlet 4 on the extension E of the retort. 95 In such a retort the only joints that require to be sealed are the two joints for the closures F and E' at the upper and lower ends of the retort.

The material in the distilling chamber is 100 supported by a laterally projecting flange 5 on the take-off duct arranged adjacent the lower end of same, as shown in Figure 1, and in practice I prefer to provide the discharge portion H of the take-off duct with 105 a laterally projecting flange 6 having a beveled surface that co-operates with a beveled surface 7 at the upper end of the extension E so as to separate the distilling chamber from the interior of the extension E at the 110 lower end of the retort in which the discharge spout 3 of the take-off duct is arranged. Accordingly, my improved retort may be said to comprise two chambers that are separated from each other by a laterally-projecting flange on the take-off duct that becomes seated automatically when the take-off duct is moved upwardly into operative position in the retort, the discharge spout at the lower end of the take-off duct 115 being arranged within the bottom chamber, and said bottom chamber being sealed or cut off from the atmosphere by the bottom closure or cover E' of the retort.

It is immaterial how the bottom closure 120 E' of the retort is mounted, but I prefer to form said closure in such a manner that it can be slipped upwardly into the extension E at the lower end of the retort and held in 125 position by one or more hinged bars 8 ar-

ranged transversely underneath same and having their free ends co-operating with latches 9, as shown in Figure 2. If desired, the bars 8 can be equipped with clamping screws 8^a, as shown in Figure 1 that are adapted to be screwed upwardly so as to force the bottom cover E' of the retort tightly against the lower end of the extension E so as to produce a tight joint for the bottom cover or closure of the retort, it being the usual practice to arrange a gasket between the closure E' and the extension E of the retort. The discharge spout 3 of the take-off duct is provided with a concaved bottom wall that is inclined downwardly towards the lateral outlet 4 in the extension E so as to cause the liquids which enter the take-off duct to flow from same into the suction main C, and if desired, a clean out opening can be formed in the T-shaped fitting 10 that connects the suction main C with the lateral outlet 4 so as to enable a tool to be run through the lateral outlet 4 into the discharge spout 3 of the take-off duct to clean same when the take-off duct is arranged in operative position in the retort and without the necessity of first breaking a joint between said take-off duct and the eduction pipe, said clean out opening being normally closed by a closure indicated as an entirety by the reference character 11 in Figure 1. While I have herein shown the bottom cover E' of the retort separate and distinct from the take-off duct, this is not essential, for if desired, the bottom cover of the retort can be integrally connected to the take-off duct, or rather, to the discharge portion H at the lower end of the take-off duct.

The distilling apparatus above described operates in the same manner as the apparatus described in my prior Patent No. 1,283,000, but it is an improvement on my said prior apparatus, in that it overcomes the necessity of using a gasket or sealing device between the discharge end of the take-off duct and the off-take pipe leading to the suction main; it overcomes the necessity of using a swivel joint in the off-take pipe, as is necessary when said off-take pipe is directly connected to the bottom closure of the retort, and it overcomes the necessity of having a workman go into the pit, disconnect the off-take pipe from the retort and then swing the off-take pipe out of alignment with the retort preparatory to lowering the take-off duct to discharge the contents of the retort. As the retort is oblong-shaped in cross section, it is practicable to arrange a number of relatively large retorts or retorts of great capacity in a bench or single setting, due, of course, to the fact that the width or transverse dimension of each retort is materially less than the transverse dimension of a circular retort of the

same capacity. And still another desirable feature of my present apparatus is that the discharge end of the take-off duct can be cleaned in case it becomes clogged or stopped up without disconnecting the take-off duct from the off-take pipe. In fact, the discharge end of the take-off duct can be cleaned out during the distilling operation by simply opening the closure 11 on the suction main and inserting a tool through the lateral outlet 4 into the discharge spout 3 of the take-off duct.

Having thus described my invention, what I claim as new and desire to secure by Letters Patent is:

1. An apparatus for distilling bituminous substances, comprising a vertical retort of substantially oblong shape in horizontal cross section provided at its lower end with an extension having a lateral outlet in the side of the same, a removable take-off duct in said retort of corresponding horizontal cross sectional shape that constitutes the sole outlet for the gases, vapors and liquids evolved in the distilling operation, and a discharge portion at the lower end of said take-off duct, arranged within the extension at the lower end of said retort and provided with a discharge opening that communicates with the lateral outlet in said extension.
2. An apparatus for distilling bituminous substances, comprising a vertical retort, a removable perforated take-off duct in said retort that is adapted to be withdrawn from the lower end of the retort, a stationary suction pipe combined with the retort, and a discharge portion at the lower end of said duct that moves automatically into and out of operative relationship with said suction pipe when said duct is inserted in and withdrawn from the retort.
3. An apparatus for distilling bituminous substances, comprising a vertical retort of approximately oblong shape in horizontal cross section, a removable, vertically-disposed, perforated take-off duct in said retort of substantially the same horizontal cross-sectional shape as the retort that is adapted to be withdrawn from the lower end of the retort, means for externally heating the retort, means for sealing off the portion of the retort that contains the material being distilled, a lateral discharge portion at the lower end of the take-off duct arranged below said sealing means, and a stationary suction pipe combined with the retort in such a way that said discharge portion will move into and out of registration with same when the take-off duct is inserted in and withdrawn from the retort.
4. An apparatus for distilling bituminous substances, comprising a vertical retort, a removable, perforated take-off duct in said retort that constitutes the sole outlet for the

- gases, vapors and liquids evolved in the distilling operation, a removable closure for the lower end of said retort, a lateral outlet leading from the side of the retort at a point above said closure, and a discharge opening at the lower end of said take-off duct, terminating inside of the retort and communicating with said lateral outlet.
5. A distilling apparatus for bituminous substances, comprising a vertical retort provided adjacent one end with a lateral outlet, a suction main communicating with said outlet, a removable take-off duct in said retort adapted to be withdrawn from one end 10 of the retort and provided with a discharge opening that aligns with said lateral outlet when the take-off duct is in operative position in the retort, and a removable closure for the end of the retort through which the 15 take-off duct is withdrawn.
6. An apparatus for distilling bituminous substances, comprising a vertical retort provided adjacent its lower end with a lateral outlet, a suction main or off-take pipe permanently combined with the retort and communicating with said lateral outlet, a removable closure for the lower end of the retort, and a removable take-off duct in said retort 20 provided adjacent its lower end with an inclined spout or discharge portion that communicates with said lateral outlet when the take-off duct is in operative position in the retort.
7. An apparatus for distilling bituminous substances, comprising a vertical retort provided adjacent one end with a lateral outlet, a suction main or off-take pipe communicating with said outlet, a take-off duct in said retort adapted to be withdrawn through 25 one end of the retort and provided with means for sealing off the section of the retort from which said outlet leads, said take-off duct having a discharge portion that communicates with said lateral outlet when 30 the take-off duct is in operative position in the retort, and a removable closure for the end of the retort through which the take-off duct is withdrawn.
8. An apparatus for distilling bituminous substances, comprising a vertical retort provided with openings at its upper and lower ends, removable closures for said openings, a lateral outlet in the side of the retort adjacent the lower end of same, a suction main or off-take pipe communicating with said outlet, a removable take-off duct in said retort that is adapted to be lowered through the lower end of the retort by a hoisting mechanism connected to the upper end of the take-off duct, and a discharge portion at the 35 lower end of the take-off duct that aligns with the lateral outlet of the retort when the take-off duct is in operative position in the retort.
9. An apparatus for distilling bituminous substances, comprising a vertical retort provided adjacent its lower end with an extension that forms a chamber which is located below the distilling chamber of the retort, a lateral outlet leading from said lower chamber, a removable take-off duct in the retort provided at its lower end with a discharge portion that communicates with said lateral outlet when the take-off duct is in operative position in the retort, and means 40 on said take-off duct for separating the distilling chamber from the lower chamber of the retort.
10. An apparatus for distilling bituminous substances, comprising a vertical retort provided adjacent its lower end with a lateral outlet, a removable take-off duct in said retort provided adjacent its lower end with an inclined discharge spout that communicates with said outlet when the take-off duct 45 is in operative position in the retort, a closure for the lower end of the retort, means for enabling a cleaning tool to be inserted through said lateral outlet into the discharge spout of the take-off duct, and means for dividing or separating the distilling chamber of the retort from the lower end portion of the retort from which said lateral outlet leads.

GEORGE W. WALLACE.
